Oscar Whitmore

By his Atty.

Alphonse Smith

UNITED STATES PATENT OFFICE.

OSCAR WHITMORE, OF OAKLAND, CALIFORNIA.

DEVICE FOR CUTTING VEHICLE-AXLES.

SPECIFICATION forming part of Letters Patent No. 368,178, dated August 9, 1887.

Application filed February 17, 1886. Renewed July 19, 1887. Serial No. 241,721. (No model.)

To all whom it may concern:

Be it known that I, OSCAR WHITMORE, a resident of Oakland, county of Alameda, State of California, have invented a new and useful 5 Machine for Cutting Vehicle-Axles; and I hereby declare that the following is a full, clear, and exact description of the same, reference being had to the accompanying drawings.

My invention relates to a machine for turning and cutting the arm of an axle of a wagon or other vehicle, and thereby adjusting the same to the worn box and obviating the use of washers.

The following description fully explains the 15 nature of my said invention and the manner in which I proceed to construct, apply, and operate the same, the accompanying drawings being referred to by figures and letters.

Figure 1 is a perspective view of the machine, showing it attached to an axle. Fig. 2 is a horizontal longitudinal section of the same, showing the supporting-plate for the cutter-bar, the chambers holding the clamps and the right-and-left-hand screws, the sleeves in said 25 chambers, the cutter-bar and crank, and the knife and the adjusting-screw. Fig. 3 is a vertical section on the line yy , Fig. 2, showing the inner chamber and sleeve, a right-and-left-hand screw, and set-screws for a pair of clamps. Fig. 4 is a vertical section on the line zz , Fig. 2, showing the outer chamber holding the same. Fig. 5 is a front elevation showing the knife and the manner of attaching the adjusting-screw thereto.

My improved machine A, for cutting axles, consists of the following parts or elements: A rear supporting-plate for the cutter-bar, having a downwardly-extending lug on each side, two boxes or chambers, each having a sleeve 40 or bearing; a pair of clamps through which extends a right-and-left hand screw and a pair of set-screws, a cutter-bar provided with a crank, and a knife placed between guide-blocks.

Referring to Figs. 1, 2, the lugs b of the 45 rear supporting-plate, b' , are bolted to the cutter-bar e , and at the head of said bar are bolted guide-blocks d d' , between which the knife e is placed. An adjusting-screw, g , passes through a lug, f , on the head of the cutter-bar, 50 and is attached to the knife in the T-shaped slot e' , Fig. 5. The cutter-bar is provided with

a crank, e' , by which the cutter-bar is turned in the operation of cutting. The outer chamber l , having a plate and sleeve, i , which passes through the hole in the cutter-bar, is attached to the inner chamber, k , by screws t , and contains in the upper or forward section a pair of clamps, n , through which and both walls of the chamber extends below the center a right-and-left-hand screw, p , one end of which is squared for the 60 action of a wrench. The object of these clamps is to center the axle and hold it rigid. On each side of the chamber there is a set-screw, s , which is set against the side of the clamp to hold the axle fixed and rigid. The plate and 65 sleeve i of chamber l is attached by screws u to the sides of said chamber, Figs. 2, 4. The inner chamber, k , is covered by a plate, v , and has a sleeve, h , which extends to chamber l , and also contains in the upper or forward section a pair of clamps, m , through which and both walls of the chamber extends above the center a right-and-left-hand screw, o , one end of which is squared for the action of a wrench. On each side of the chamber there is a set-screw, 70 r , which is set against the side of the clamp to hold it to the axle in a rigid manner. Both chambers l k are attached by screws t , Fig. 2.

The axle may be centered by a single pair of clamps; but I prefer the joint action of two 80 pairs and employ them in my machine, and while a good bearing for the axle may be obtained by a single sleeve I preferably employ two, one in each chamber, as shown in Fig. 2.

The machine is set by slipping the axle into 85 the sleeves or bearings and through both chambers, and both pairs of clamps are centered upon and grip the axle by the action of the right-and-left-hand screws, which are set by a wrench. The set-screws are then adjusted to 90 the sides of the clamps, which they hold rigidly to the axle. When the axle is set to the required gage for cutting, the cutter-bar holding the knife is turned, by which action a shaving is cut off the axle. After each cut the knife 95 is adjusted to the axle by the adjusting-screw, and this operation is repeated until the cut is completed.

Having thus fully described my invention, what I claim, and desire to secure by Letters 100 Patent, is—

In an axle-cutter, the combination of the

chambers *k l*, bearings or sleeves *h i*, having plates, right-and-left-hand screws *o p*, adjustable clamps *m n*, set-screws *r s*, rear supporting-plate, *b*, having lugs *b'*, cutter-bar *c*, having crank *c'*, knife *e*, having a T-shaped slot, guide-blocks *d d'*, and adjusting-screw *q*, substantially as and for the purpose set forth.

In witness whereof I have hereunto set my hand and seal.

OSCAR WHITMORE. [L. S.]
